UNITED STATES PATENT OFFICE.

GEORGE RETTIG, OF CHICAGO, ILLINOIS.

TYPE-CASTING MACHINE.

SPECIFICATION forming part of Letters Patent No. 354,935, dated December 28, 1886.

Application filed January 12, 1885. Serial No. 1,2,696. (No model.) Patented in Germany February 17, 1886, No. 36,420.

To all whom it may concern:

Be it known that I, GEORGE RETTIG, a citizen of the United States, and residing at Chicago, in the county of Cook and State of Illinois, have invented certain new and useful Improvements in Type-Casting Molds, which are fully set forth in the following specification.

The purpose of this invention is to provide means whereby the "jet" or tongue of refuse metal, which fills the port of a type-casting mold from the base of the type to the nipple-plate, may be detached from the type in the act and process of opening the mold, and may also automatically by the operation of the machine be removed from its lodgment in the mold-port, so that the same may be clear for the flow of the metal for the next type.

In general it consists of two parts or features—the first, the means for detaining the jet while the type is removed and so effecting separation between them, and the second the means for clearing the jet from its lodgment in the port.

The first part consists in providing some portion of the fixed member of the mold with recess or recesses communicating with the jet-port, into which some portion of the metal may flow and form detent points or flange on the jet, whereby it may be detained in the fixed member of the mold, as set forth. I prefer to accomplish this by providing in the nipple-plate or apron on the inner face, which abuts against the mold, a hollowed recess adjacent to and merging in the nipple-orifice, commonly called the "spout," at the lower side thereof, being in the nature of an eccentric countersink to the spout, and providing in the edge of the lower or stationary member of the mold, as close to the upper surface as possible and in such position as to open into the said recess in the nipple-plate, small holes of slight depth, into which the metal discharged through the spout in the nipple-plate to fill the mold and form the type shall flow and constitute, when hardened, detent-points, whereby the jet may be held in the fixed member of the mold, while the type retained in the upper or vibrating member by the usual means—a pin-print—is broken off from the jet in the action of opening the mold, so as to be separately discharged. The flange of metal

formed in the recess in the nipple-plate will, in some cases, be sufficient for the purpose of detaining the jet without the addition of the projecting points formed in the holes made in the mold itself, and the latter may therefore be omitted; or, instead of or in addition to both flange and projections to insure the result, provision may be made for a projection from the side of the jet by providing a recess in that lateral wall of the jet-port which is formed by the lower member of the mold.

The second part consists in suitably connecting to any part of the machine other than the mold itself, but which is actuated synchronously with the opening of the mold, a lever arranged and adapted to be moved by such moving part past the rear edge of the lower member of the mold to discharge the jet.

Figure 1 is a rear elevation of a type-mold in position on the machine and provided with my invention—viz., devices for detaining and discharging the jet. Figs. 2 and 3 are horizontal isometrical projections, respectively, of the upper and lower members of the mold, their opposing faces being exposed to view. Figs. 4 and 5 are vertical isometrical projections, respectively front and rear, of the lower member of the mold, the latter showing also the nipple-plate and the position of its spout relatively to the jet. Fig. 6 is an inner side elevation of the plate, showing the recess or countersink about and below the nipple-orifice or spout. Fig. 7 is a section through *xx* in Fig. 6. Figs. 8, 9, and 10 are detail views of different forms of the recess in the nipple-plate and its relation to the spout. Figs. 11 and 12 are details showing the form of the jet as produced in a mold having my invention applied. Fig. 13 is a side elevation showing the actuating parts of the rocking frame *X* and of the lever *E*.

A is the upper member of the mold. *A'* is the lower member.

a is the jet-port through which the metal enters the mold, being bounded by the faces *a'* and *a''* of the lower member, *A'*, and by the faces *a³* and *a⁴* of the upper member, *A*, having, therefore, and giving to the jet the wedge-shaped form shown in Figs. 11 and 12, thinness at its junction with the base of the type, so as to be easily detached at that point. The faces *a⁴* and *a⁵* of the lower member and *a⁶* and

*a*⁷ of the upper member bound the type-cavity, the two members being relatively adjustable for different sizes of type, as well understood. The face *a*⁶ of the upper member has the usual 5 detent pin or pins, *c*, to detain the type in that member when the mold is opened.

B is the nipple-plate, through whose spout *b* the metal reaches the jet port *a*, as shown in Fig. 5.

10 *b'* is the recess on the inner surface of the nipple-plate.

b'' are pin-holes in the edge of the mold and within the bounds of the recess *b'*.

15 *b'* is a recess in the lateral wall *a'* of jet-port in the lower member of the mold, wherein is formed a lateral projection from the jet. When used alone, without the recesses *b'* and *b''*, it may be located nearer the larger end of the jet; but when used in conjunction with 20 recesses *b'* and *b''* its location is preferably nearer to the smaller end of the jet and to its junction with the type.

25 The metal flowing through the spout *b* will fill the recess *b'*, and thence pass into the holes *b''*, while the other portion of it flows on through the jet-port *a* and into the mold to form the type. When the mold has withdrawn from the nipple-plate and opened, as in the ordinary operation of type-casting machines, the 30 flange and projections formed in any or all of the several recesses described in the nipple-plate and the lower member of the mold detain the jet therein, while the body of the type detained by the usual means—the pin *c*—35 in the upper member is broken off from the jet at the base of the type, where the jet is thinnest.

40 I find it desirable to produce the recesses described by drilling in the mold before it is hardened small pin-holes, and after the mold is hardened driving into such pin-holes soft iron or steel pins or plugs *b'*, leaving only the desired depth of recess in front of the pin, so that if in dressing up the mold, as is done 45 to insure and preserve its accuracy, those recesses which are very slight should be "dressed out" they may be readily restored by driving in or cutting into the soft pins which fill the holes.

50 In order to discharge the jet and clear the mold for the next type, I have provided the arm *D*, which, as illustrated, is a lever pivoted to any part of the machine, which is fixed in its position relatively to the lower member of 55 the mold—as to the rocking frame *X*, which carries the entire mold. Said arm *D* is connected by the link *D'* to any part, as the arm *E*, which moves while the mold is open, and is thereby actuated, so as to cause the free end 60 *D'* to move close to the rear side of the fixed member *A'* of the mold and strike the projecting points *e* of the jet and detach and discharge it from the mold.

65 I provide several of the holes *b''*, to adapt the device to all sizes of type to which the mold is adapted.

I do not limit myself to the use of separate

holes *b''*; but a continuous groove might be substituted, though with the disadvantage that the entire groove would fill with metal 70 even in making small type. When the separate holes are used, the lateral extent of the recess *b'* should be only sufficient to embrace one or two of them, and as the position of the spout is changed for different sizes of type 75 different holes, but not more of them, will be brought into use.

The structure of the type-casting machine in connection with which my invention is shown is the familiar one, the rocking or 80 vibrating frame *X* being pivoted at *x* to the base or main frame of the machine *X'* and caused to rock over the said pivots by the cam *Y* on the revolving shaft *y*, the arm *E* being vertically oscillated by the said rocking motion of the frame *X* by means of the connecting rod or lever *Z*, which is pivoted by ball-and-socket joints *z* and *z'* to the base-frame *X'* and the arm *E*, respectively; but my invention is independent of this particular structure, and in a differently-constructed machine 90 the arm *D* might be actuated by a different and differently-actuated part without departing from the substance of my invention, for I do not limit myself to the precise arrangement of the arm *D*, nor to so connecting it 95 that its motion shall be that of a lever, nor to connecting it to the arm *E*; but any arm actuated at the time the mold is open by connection with a moving part of the machine, 100 and located so that it shall in its motion strike the projecting points of the jet to dislodge it from the mold, will be within the scope of my invention.

I do not claim, broadly, providing the two 105 members of the mold one with a type-detainer and the other with a jet-detainer, whereby the opening of the mold breaks the jet from the type; nor do I claim, broadly, combining with a mold so constructed an arm 110 which moves past the jet end of the jet-detaining member after the breaking is effected to discharge the jet, for I am aware that such an arm has heretofore been used, rigidly fastened to the moving member of the mold and moving 115 past the fixed member, which is made to retain the jet; nor do I claim to be the first to employ the recesses to form on the jet the detent to hold it in the mold, nor to be the first to combine with a mold having recesses for 120 such purpose a jet-discharging arm actuated by a moving part of the machine and moved close to the jet end of the mold; but

What I claim is—

1. In combination with the mold having a 125 jet-casting portion, the nipple-plate or apron provided on the face toward the mold with a recess adjacent to and merging in the aperture through said plate by which the metal is conducted to the mold, said recess extending laterally beyond the jet-aperture of the mold, whereby a flange is cast on the jet against the face of the mold, substantially as set forth.

2. In a type-casting mold, in combination

with the nipple-plate having a recess on its inner face adjacent to and merging in the spout, the lower or stationary jet-block provided with recess or recesses in its rear edge 5 communicating with the recess in the nipple-plate, substantially as set forth.

3. In a type-casting mold, in combination with the movable type-detaining member of the mold, the nipple-plate having a recess on its inner face adjacent to and communicating with the spout, the lower or fixed member of the mold having in its rear edge a recess or recesses communicating with the recess in the nipple-plate, and having also a recess in the 15 lateral wall of the jet-port, substantially as set forth.

4. In a type casting machine, in combination with the fixed member of the mold and the arm which actuates the vibrating member, 20 the arm D, actuated by means of suitable connection with the arm which actuates the vibrating member of the mold, but independently of said member, and located and adapted to move close and parallel to the rear face of 25 the fixed member of the mold while the same is open, substantially as set forth.

5. In combination with the jet-retaining member of the mold, an arm pivoted on the mold-carrying frame and actuated during the

opening of the mold past the jet end of said 30 jet-retaining member, substantially as and for the purpose set forth.

6. In a type-casting machine, the fixed member of the mold A, having recesses to form detents on the jet, the arm D, the link D', and 35 the arm E, combined and co-operating as and for the purpose set forth.

7. In a type-casting machine, the mold having in its vibrating member detents to detain the type and in its fixed member devices to 40 detain the jet, in combination with the arm E, the link D', and the lever D, substantially as and for the purpose set forth.

8. In a type casting mold, the lower or fixed member having holes leading from the jet port 45 or cavity communicating therewith, and provided with pins or plugs of softer metal than the body of said mold, substantially as and for the purpose set forth.

In testimony whereof I have hereunto set 50 my hand, in the presence of two witnesses, at Chicago, Illinois, this 5th day of January, A. D. 1885.

GEORGE RETTIG.
